COMBINATION TOOL

Arthur J. Hoeflicker, Long Beach, Calif.

Application November 22, 1948, Serial No. 149,760

Term of patent 14 years

(Cl. D54—16)

To all whom it may concern:

Be it known that I, Arthur J. Hoeflicker, a citizen of the United States of America, residing in the city of Long Beach, California, in the county of Los Angeles, State of California, have invented a new, original, and ornamental Design for a Combination Tool, of which the following is a specification, reference being had to the accompanying drawing, forming a part thereof.

Fig. 1 is a side elevational view of a combination tool showing my new design; and

Fig. 2 is a plan view of the device.
I claim:

The ornamental design for a combination tool, substantially as shown.

ARTHUR J. HOEFLICKER.
